(57) **CLAIM**

(21) Appl. No.: **29/324,462**

The ornamental design for a piston with x-shaped groove in the skirt, as shown and described.

(22) Filed: **Sep. 12, 2008**

DESCRIPTION

(51) **LOC (9) Cl.** **15-01**

FIG. 1 is a perspective view of a piston with X-shaped groove in the skirt showing our invention;

(52) **U.S. Cl.** **D15/5**

FIG. 2 is a top plan view thereof;

(58) **Field of Classification Search** D15/5-6;

FIG. 3 is a bottom plan view thereof;

123/193.1, 193.6, 47 A, 47 R, 41.35, 661,
123/659; 92/172, 224, 229

FIG. 4 is a front plan view thereof;

See application file for complete search history.

FIG. 5 is a rear plan view thereof and a reverse view of FIG. 5;

FIG. 6 is a left side view thereof; and,

(56) **References Cited**

FIG. 7 is a right side view thereof.

U.S. PATENT DOCUMENTS

The broken line showing portions of a piston with X-shaped groove in the skirt is included for illustrating environmental structure and forms no part of the claimed design.
